UNITED STATES PATENT OFFICE.

FRIEDRICH W. GILLES, OF KALK, NEAR COLOGNE, GERMANY.

IMPROVEMENT IN GAS-ENGINES.

Specification forming part of Letters Patent No. **179,782**, dated July 11, 1876; application filed May 18, 1876.

To all whom it may concern:

Be it known that I, FRIEDRICH WILHELM GILLES, of Kalk, near Cologne, Germany, have invented certain new and useful Improvements in Gas-Engines; and I do hereby declare that the following is a full, clear, and exact description of the same, reference being had to the accompanying drawing, which forms part of this specification.

This invention relates to engines for obtaining motive power by the explosive combustion of gas and air, and has for its objects, or certain of them, the working of the engine with but little or no noise, and at a reduced cost, together with great simplicity as regards construction of the engine and facility of repair.

The invention especially relates to a combination of parts whereby the pressure produced by the ignition of an explosive gaseous mixture in the cylinder of the engine is applied to propel two pistons in opposite directions—that is to say, a working-piston and a loose piston, the former of which is connected by crank with a driving-shaft, and the latter of which is free, but is temporarily held by a clamp after its propulsion by the explosion of the gaseous compound, to secure the return action of the working-piston under atmospheric pressure as against a reduced pressure between the two pistons, thereby obtaining a motive power for the working-piston in both directions of its stroke.

The invention consists in a peculiar construction and combination of devices for clamping and releasing the free piston in timely relation with the working or driving piston of the engine.

The invention likewise consists in a combination, with the engine, of a certain regulating pump or apparatus for automatically controlling the speed of the engine.

In the accompanying drawing, Figures 1 and 2 represent sectional elevations in planes at right angles with each other of a gas-engine constructed in accordance with this invention.

The engine is here represented as occupying an upright position, and the following description will be made in accordance with such

an arrangement by way of simplifying explanation; but so far as all practical purposes are concerned, said engine may occupy a horizontal or any other suitable position without departing from the invention.

A is the bed-plate, on which is erected the main frame of the engine. B is an elongated engine-cylinder, mounted on the main frame, and freely open at its lower end. H is the lower and working or driving piston, arranged to reciprocate within the cylinder B, and coupled by a connecting-rod, b, with a crank, K, of a driving-shaft, I, on which is a fly-wheel, J. L is the upper or loose piston, also arranged to reciprocate within the cylinder B, and provided with a rod, c, which passes up through the top of the cylinder, and through two friction cheeks or clamps, l l, formed by a longitudinally-divided bush, which clamps the rod c in between it. These clamps are freely mounted on a lever or levers, m, and are so constructed with notches, inclines, or steps, and controlled by springs n n, entering at an upwardly-inclining angle within or bearing on the notched surface of the clamps, that while the clamps admit of the free movement of the piston-rod c, when traveling in an upward direction between them, they hold or restrain it and the piston L from moving downward by tightly embracing the rod c until the clamps are relieved by the action of a cam, O', on the main shaft I, by or through the intervention of a rod, d, which, when raised, lifts the levers m and pushes upward the clamps l l, thus relieving the piston-rod and allowing the piston to descend. This liberation or release of the clamps occurs at a certain point in each revolution of the crank-shaft.

On the one side of the cylinder B, at a suitable position in relation with its length, is a valve chest or chamber, D, which is in communication, by a passage, a, with the cylinder B, and which, furthermore, has ports b' c' for the admission of gas and air, or of the gaseous mixture and air. These ports or passages, as also an additional air-supply port or passage, h', to the burner i, by which the explosion is affected, are controlled by a gas slide-valve, D', arranged to work within the chamber D,

and constructed with cavities or passages p y through it. Said valve also carries the burner i , and is operated by a cam, O , on the driving-shaft I , through a rod, e' , as against a spring, f' .

Arranged somewhat higher up the cylinder B than the valve-chamber D is a valve-chamber, N , provided with a valve, N' , opening outward for the discharge of products of combustion from the cylinder by a main passage, W , and a subsidiary passage, Q , the latter passage having its capacity for discharge controlled by a regulating-screw, s .

The operation of the engine is as follows: Assuming the working-piston H to have reached the extreme of its inward or up stroke, the piston L then being close to it, as shown in Fig. 1, the former piston, H , by the rotation of the crank K , is drawn down or outward, and the loose piston L , backed by pressure of the atmosphere entering through an opening in top of the cylinder, follows the working-piston H till the loose piston L is checked at the extremity of its down-stroke by a stop, r , on its rod coming in contact with an upper frame on the top of the cylinder, as shown in Fig. 2. The working-piston H , continuing its downward movement, creates a partial vacuum behind it, in the space between it and the loose piston L . As, however, this begins to take place, the cam O moves the gas-slide D' , so as to admit into this space between the two pistons, from the receiving-passage p of said valve, the gaseous mixture, and during the further rapid movement of said valve exposes the kindling-flame of the burner i to the gaseous mixture in the cylinder through the passage a , whereby the mixture is exploded.

The pressure produced by the explosion forces still further downward or onward the working-piston H , and at the same time causes the loose piston L to make a rapid stroke in an upward or opposite direction, the air in the space at back of the loose piston being discharged through the head or top of the engine-cylinder. When the loose piston at the extreme of its top stroke enters and closes by a projection on it this air-opening in the head of the cylinder, the inclosed air serves as a cushion to check the loose piston, a spring-valve being used in addition, if desired, to provide for a slow escape of the compressed air.

The working-piston H having completed its down or outward stroke, and the loose piston L having also completed its up or outward stroke, and the gas-slide D' having closed the passage a , or space between the two pistons, the cylinder-space between the two pistons remains charged with the products of combustion at a pressure considerably below that of the atmosphere. The atmospheric pressure consequently tends to force both pistons inward or toward each other. The working-piston H moves inward in obedience to this

pressure, but the loose piston is held near the extreme of its out-stroke by the friction cheeks or clamps l l , hereinbefore referred to, the ingress of air at the back of it being checked.

When the working-piston H is approaching the extremity of its in-stroke, the clamps l l are released by the action of the cam O' from hold of the loose piston L , and the discharge-valve N' is opened. This causes the loose piston L to make a rapid stroke inward till it nearly meets the working-piston H , as shown in Fig. 1, and the products of combustion compressed between the two pistons are forced out by the passage W through the discharge-valve N' , after which the action is repeated, as before. The subsidiary passage Q , arranged a little below the passage W , provides for the escape of any remaining products of combustion between the two pistons after the passage W has been stopped by the loose piston, and the screw s , controlling such subsidiary passage Q , serves to regulate such escape and to retard the same, as required, whereby a buffer-like action is produced between the two pistons.

From the foregoing description it will be seen that the engine is double-acting, a portion of the out-stroke of the working-piston being effected by the pressure incidental to the explosion of the gaseous mixture between the pistons, and its in-stroke by the excess of the atmospheric pressure over that of the products of combustion.

Two or more engines may be connected to one driving-shaft, so as to diminish irregularities of action.

By placing the engine-cylinder in an upright position, the weight of the working-piston is made available to assist the out-stroke of the latter, and the loose piston is assisted by its weight in its in-stroke.

In connection with the gas-valve D' is a regulating pump or device, R , which, by means of a lever, g , between stops on the rod e' , is worked by the same cam, O , which operates the gas-valve D' . The piston or sucker k of this pump draws in and expels a certain amount of liquid at each revolution of the engine-shaft. If the engine be running too fast, all the liquid drawn in cannot be expelled. This causes the lever g to be lifted and hold and raise the rod e' and valve D' , so that a new charge of gas cannot be given until the speed of the engine has been reduced.

I claim—

1. The combination, with the free piston L of the engine and its rod e , of the clamp or clamps l , the lever m , controlled by the cam or eccentric O' of the engine, and the inclined springs n , arranged to bear the clamps against the rod e , to hold the piston L from moving inward, excepting when the clamps are specially released for the purpose, but admitting of the free movement of said rod in

the outward stroke of said piston, essentially as described.

2. The combination, with the gas-valve D', of the pump R, the pump-operating lever g, controlled by stops on the valve-rod e', and the cam O, by which motion is communicated to both the valve and the pump, substantially as and for the purposes herein set forth.

In testimony that I claim the foregoing I have hereunto set my hand this 30th day of August, 1875.

FRIEDRICH WILHELM GILLES.
